A. HODGES

J. F. Dowling, Attorney

UNITED STATES PATENT OFFICE.

ARTHUR HODGES, OF BALTIMORE, MARYLAND.

GAME APPARATUS.

Application filed January 30, 1923. Serial No. 615,824.

To all whom it may concern:

Be it known that ARTHUR HODGES, citizen of the United States, residing at Baltimore city and State of Maryland, has invented 5 certain new and useful Improvements in Game Apparatus, of which the following is a specification.

This invention relates to certain new and novel improvements in game apparatus, and has for one of its principal objects the provision of a simple and entertaining apparatus for use in playing a game of which the purpose is to simulate the traveling through all the States of the Union and possessions of the United States by several players indicated by objects, which objects must be confined in their movements between stops or stations, and the extent or relative movements of the objects or players being determined by a suitable spinner, such as a dial, or the like.

A further object of the invention is to provide a game apparatus including a surface having depicted thereon a circle divided into rectangles, each rectangle constituting a State, a second circle within the first circle also being divided into rectangles and indicating the possessions of the United States, certain of said States being numbered and 25 depicted in colors, and constituting the advancement or the retarding of the players according to the rules laid down.

With these and other objects in view the invention consists in certain novel features, combination and arrangement of parts as 35 shown in the drawing and pointed out in the claims hereto appended.

Figure 1 is a plan view of a playing board constituting the main feature of the game apparatus.

Figure 2 is a transverse sectional view taken of the line 2—2 of Figure 1.

Figure 3 is a plan view of a dial or movement controlling device for the game apparatus.

Figure 4 is a plan view of the game pieces, and

Figure 5 is a perspective view of a modified form of the game board showing the 50 same made of cardboard, so that it may be readily folded if desired.

Referring to the drawing, the numeral 10 indicates a game board which is of any suitable construction and has depicted thereon 55 a pair of relatively spaced circular lines 11,

which circular lines are divided by transverse lines 12, which division made by the lines 12 constitutes all of the States of the Union, each State being a substantially rectangular block and having its name depicted to one side thereof. Certain of the States are numbered from 1 to 22, respectively, and these States indicated by numbers in a circle are in different colors, States 1, 4, 5, 6, 10, 13, 17, 18, 20 and 21, being in red, and the 60 remaining numbers in the circle being in blue. The surface board has also depicted thereon, a second pair of circular lines located within the first pair of lines and indicated by the numerals 13, which second pair 70 of lines are divided by transverse lines 14, which lines 14 form divisions defining rectangular squares and constituting the possessions of the United States and have depicted thereon the various names. 75

I have provided a series of arrows constituting paths which extend from the inner circle of the first pair of circular lines, and these arrows extend in the direction of the outer circle of the inner pair of circular 80 lines. The arrows are indicated by the numeral 15 and form paths whereby the players may advance from certain States in the outer circles to certain possessions in the inner circle and by required movements complete the circuit thereof, and then go back to certain States in the first pair of circular 85 lines.

This is accomplished by certain movements on the dial, and should a player hit 90 certain States such as Delaware or New York, he advances into the inner circles, either the Philippines or Panama, and completes a circuit of these various possessions and then goes back to certain of the States 95 and starts his movements about the States over again.

The starting point is indicated by the letters "W. C. T. U.", and the finish is indicated by the words "18th Amendment," 100 the object being to start from the letters "W. C. T. U." and advancing around and touching each State, and necessarily traversing around the circle. The player advancing to any of the red stations, such as 105 1, 4, or the like, is retarded and either returns to W. C. T. U., or loses one or more spins. If he touches a blue station indicated by the numerals 2, 3, 7, or the like, he advances one or more stations, or has extra 110

spins. In other words, in traveling around the circumference of the circles indicated on the board surface, the player is more or less governed by the number indicated by the spinner and if it is 1 or 4 he makes such a move, and should he rest upon numerals 1, 4, 5, 6, 10, 13, 17, 18, 20 or 21, he either returns to W. C. T. U. or returns a certain number of States, or loses a certain number 10 of spins. In other words, the red stations indicate retarding stations, and the blue stations indicate advancing stations, it being understood that the game is played in accordance with a certain set of rules which 15 are laid down for the guidance of the participants of the game.

The indicators or objects representing the players are of the type such as are used in checkers or similar games, and one or more 20 players may participate, the player reaching the 18th Amendment first, having traversed the entire circumference of the game surface, wins the game.

It will be obvious that by adopting more 25 or less restrictive rules of play the game may be made as difficult as desired and will afford entertainment in the fact that the game surface is divided up into advancing and retarding stations, which are reached according 30 to the number depicted by the spinner, and when one reaches either an advancing or retarding station he must act according to the rules laid down, it being understood that these advancing or retarding stations may 35 be varied like chess and other games, so as to make it necessary for the player to calculate in advance the moves which should be made in order to accomplish the desired object, that is, reaching the 18th Amendment. 40 The spinner indicated in Figure 3 is designated by the numeral 16 and is of the usual type having depicted thereon several numbers 17, over which travels a rotating arrow 18 and the objects or playing pieces,

as illustrated in Figure 4, are indicated by 45 the numeral 19.

Now referring to the structure illustrated in Figure 5, I form my game surface on a relatively heavy piece of pliable material such as pasteboard, canvas, or the like, and 50 is indicated by the numeral 20 and on one surface of this board is depicted the game surface 21.

It is to be understood that the modified form shown in Figure 5 may be folded centrally so as to be placed away in a small and convenient space. 55

Having thus described my invention, what I claim as new is:

1. A game apparatus having a playing 60 surface for traverse by playing objects, said surface being divided by circular lines, which in turn are divided into rectangular spaces constituting States, certain of said States being colored and numbered and constituting retarding or advancing stations, and means associated with said game surface to govern the movements of the objects to the States, and the States governing their forward or retard movement. 70

2. A game apparatus having a playing surface for traverse by playing objects and having depicted thereon a pair of circular lines divided into rectangular spaces constituting States, a second pair of circular lines 75 located within the first pair and divided into rectangular spaces to constitute Territories, arrows depicted on the surface and constituting pathways from the outer circle to the inner circle, certain of said States being colored to govern the retarding or advancing movements of the playing objects, and a dial or counter to regulate the movements of the objects. 80

In testimony whereof I hereunto affix my 85 signature.

ARTHUR HODGES
